DOUBLE COLLAR

Rudolf Pracht, Breslau, Germany, assignor to the firm Hermann Tschentschel, Maschinenfabrik, Breslau, Germany, a partnership composed of Erich Tschentschel, Gerold Tschentschel, Alfred Tschentschel, and Elisabeth Thomas, née Tschentschel, all of Breslau, Germany

Application November 13, 1934, Serial No. 752,816
In Germany December 31, 1930

4 Claims. (Cl. 2—138)

Application has been filed in Germany on December 31, 1930.

The present invention relates to stiff and half-stiff double collars made of any suitable material 5 and provided with a device for facilitating the drawing of the tie through the collar.

Double collars are already known which are provided with narrow perforations arranged transversely or at an angle to or longitudinally 10 of the neck band of the collar, or with narrow grooves on the neck band which are directed towards the outer portion of the collar. In collars of this known kind, however, the ease of manipulation in drawing the tie through the 15 collar is not increased, but rather on the other hand a pressing action on the strip of the tie is exerted in consequence of the narrowing of the intermediate space between the inner and outer parts of the collar. Stiff double collars are likewise known which, for the purpose of facilitating 20 the operation of drawing the tie through, are provided with a strip of material attached below the fold-over part of the collar on the inner side. Furthermore, stiff double collars are also known 25 which are provided on the inner part or neck band with two longitudinal bulges spaced apart from one another, the neck tie being inserted between the bulges so that it can freely slide between them.

30 This last named construction has, however, the disadvantage that the longitudinal bulges which provide a space between them for the purpose of enabling the tie to be conveniently drawn through between the folds of the collar have to be first sewn on to the inner wall of the neck band of the collars whether they are new or whether they have been already used. This necessity considerably increases the cost of 35 manufacture of the double collar. A still more important disadvantage results, however, from the fact that when a collar of this kind is ironed, the bulges which are intended to form the intermediate space for the passage of the collar become ironed out flat and thereby rendered inoperative.

In the stiff double collars according to the present invention, these disadvantages are avoided by the provision of a longitudinal depression which is pressed out from the otherwise 50 unaltered interior wall of the neck band of collars which may be new or may have already been used. It will be obvious that a depression produced in this way and extending longitudinally around the neck band so as to enable the tie to be readily passed around the same, will remain

always operative. The depression pressed out of the neck band is of curved or arcuate form.

As compared with the known collars having special devices for obtaining the result aimed at, namely for facilitating the drawing of the tie 5 between the outer and the inner part of the collar, the present invention offers the further particular advantage that the depression can be produced after manufacture on any existing collar by means of a simple machine adapted for 10 this purpose.

By way of example a collar made according to the invention is illustrated on the accompanying drawing, in which:

Fig. 1 is a perspective front view of a stiff 15 double collar,

Fig. 2 is a cross section through the collar, and

Fig. 3 is a view of the collar similar to that shown in Fig. 1, but in which the one corner of the front portion of the outer part of the collar 20 has been cut away.

Referring to the drawing:

A stiff double collar 4 is shown which is provided with an outer portion 1 and an inner portion or neckband 2. According to the invention 25 the neckband is formed with a longitudinal hollow chamfer or depression 11 projecting inwardly, that is to say towards the neck of the wearer. By the provision of the said depression an enlarged space 5 is advantageously provided 30 for the reception of the band 6 of a neck tie inserted between the two portions of the collar.

I claim:

1. A stiff double collar comprising an outer portion and a neck band, the neck band being 35 provided with a longitudinal depression and the outer portion being convex, substantially as and for the purpose described.

2. A stiff double collar made in one integral piece and comprising in combination: an outer 40 portion of single thickness; and an inner neck band of the same single thickness forming a fold with said outer portion and provided with a longitudinal inwardly extending depressed part of arcuate cross section pressed out from said neck 45 band, substantially as and for the purpose described.

3. A stiff double collar made in one integral piece and comprising in combination: an outer portion of single thickness; and an inner neck 50 band of the same single thickness forming a fold with said outer portion and provided with a pressed-out part of the aforesaid single thickness extending longitudinally and horizontally around the middle portion of said neck band, said 55

pressed-out part being of arcuate cross section and having its convex side directed inwardly towards the neck of the wearer of the collar, substantially as and for the purpose described.

4. A stiff double collar comprising in combination: an outer portion of single thickness; an inner portion of the same single thickness integral with said outer portion and forming a fold

therewith, said inner portion constituting a neck band; and a longitudinal depressed part on said inner portion integral with and having the same single thickness as the latter, said depressed part being of concavo-convex cross section and having its convex side on the side of said inner portion remote from said outer portion. 5

RUDOLF PRACHT.
